[57] CLAIM

The ornamental design for a snow ski and pole carrier, as shown and described.

DESCRIPTION

FIG. 1 is a perspective view of the snow ski and pole carrier.

FIG. 2 is a top view of the snow ski and pole carrier with loop sewn at each end and pole straps extended flat.

FIG. 3 is a right side view of the snow ski and pole carrier.

FIG. 4 is a right side elevation view of the snow ski and pole carrier as seen when in use. Broken lines indicate environmental structure and form no part of the claimed design.

FIG. 1

FIG. 2

FIG. 3

FIG. 4
